Primary Examiner — Barbara Fox(74) *Attorney, Agent, or Firm* — NSIP Law**CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged bottom view in which the electronic device is provided in a closed position to illustrate an example environment.

The broken lines shown in the drawings represent portions of the electronic device which form no part of the claimed design.
